UNITED STATES PATENT OFFICE.

WILLIAM E. FOWLER, JR., OF HAMMOND, INDIANA, ASSIGNOR TO SIMPLEX RAILWAY APPLI-
ANCE COMPANY, OF CHICAGO, ILLINOIS, A CORPORATION OF ILLINOIS.

BRAKE-HEAD.

No. 920,944.

Specification of Letters Patent.

Patented May 11, 1909.

Application filed June 29, 1908, Serial No. 440,975. Renewed February 26, 1909. Serial No. 480,158.

To all whom it may concern:

Be it known that I, WILLIAM E. FOWLER, Jr., a citizen of the United States, residing at Hammond, in the county of Lake and State 5 of Indiana, have invented certain new and useful Improvements in Brake-Heads, of which the following is a specification.

My invention, which pertains to railway-car brake-beams, has for its main and principal purpose the provision of a brake-beam with brake-heads which will be securely held thereon from movement lengthwise of the beam, and which may readily be adjusted angularly thereon, and maintained in adjusted 10 position by a simple and effective locking means. In the preferred and most desirable embodiment of the invention, each end of the beam has a sleeve externally grooved transversely, the groove having one or more open 15 mouths or entrances for the admission of a lug or projection on the inner surface of the brake-head hub, this projection and groove forming a bayonet joint and preventing displacement of the head longitudinally on the beam. The bottom of the groove is preferably roughened, and co-acting with such surface I provide a locking block mounted in a 20 recess or pocket in the brake-head, and actuated or pressed into locking engagement with the sleeve by a slid- 25 able wedge in the recess back of the lock-block, this wedge having an aperture accommodating the head of a bolt, the other end of which is extended outwardly through a hole in the brake-beam head, and 30 being equipped with a nut adapted to actuate the wedge and force the lock-block against the roughened surface of the sleeve to hold the head in adjusted angular position.

A desirable embodiment of this invention 35 is illustrated on the accompanying drawing forming a part of this specification, and to which reference should be made in connection with the following detail description.

On the drawings,—Figure 1 is a substantially central vertical section through the 40 brake-head and sleeve forming a part of the brake-beam; Fig. 2 is a section on line 2—2 of Fig. 1 as viewed in the direction indicated by the arrows; Fig. 3 is a top plan view of the 45 brake-beam sleeve; and Figs. 4 and 5 are fragmentary sections illustrating the manner of positioning the locking block and wedge in the pocket or recess of the brake-head.

Referring to the drawings, it will be noted 50 that the brake-beam has a compression bar

10 and a tension rod 11, on the ends of which is fitted a sleeve 12 having the customary and usual flange 13 at one end, and also having on its exterior surface a curved groove or slot 14 with right-angle extensions 15 and 16 at its opposite ends and leading to the ends of the sleeve, as is clearly indicated in the figures. The bottom of this groove 14 on the top and bottom of the sleeve is serrated or toothed or roughened at 17 and 18, for a purpose hereinafter indicated.

The brake-head 19 is supplied in its lower portion with a pocket or recess 20 having a curved entrance or mouth 21 somewhat narrower than the full width of the pocket. My 55 improved locking means includes a lock-block 22 having a concave roughened or serrated surface 23 on one side, the opposite surface of the block being inclined or beveled at 24. This block, as is clearly shown in the drawings, is adapted to fit in the mouth of the recess or pocket and extend out of the same into the groove 14, the roughened surfaces of the block and the bottom of the groove co-acting as will be readily understood. 60 Also in this pocket or recess 20 I provide a sliding wedge 25, the inclined surface of which bears against the corresponding surface 24 of the lock-block, while its opposite face rests upon and is adapted to slide upon the bottom of the recess or pocket. On its 65 under face this wedge 25 has an undercut recess or cavity 26 adapted to accommodate and receive the head 27 and a portion of the shank of a bolt 28, the co-operation of the 70 parts being shown in Figs. 1, 2 and 4. The side walls of the pocket or recess 20 are apertured or perforated at 29 and 30, through either one of which holes the shank of the 75 bolt 28 is adapted to be passed, a nut 31 on the end of the bolt being used to draw the wedge or inclined surfaces of the wedge-block 25 and the lock-block 22 together to force the lock-block into firm engagement with the 80 roughened surface of the sleeve. A nut-lock 32 of any usual and ordinary character may 85 be employed to co-act with the nut and the brake-head to prevent loosening or unturning of the former.

The interior cylindrical surface 33 of the 90 hub 34 of the brake-head is supplied with an inwardly extended projection or lug 35 adapted to fit in the groove 14 and prevent 95 lengthwise or longitudinal shifting of the head on the sleeve or beam, this lug 35 when 100

the head is being placed on the beam passing into the slot 14 through one or the other entrances or mouths 15 or 16. In some cases it may not be necessary to use this projection 5 or lug 35, but in the preferred form of my device I employ such a construction, and have therefore illustrated the same on the drawings; and when such a lug is not used reliance is placed solely upon the lock-block 10 22 to prevent longitudinal movement of the head on the beam.

The parts of this device are assembled in a manner substantially as follows: The bolt 28 having been placed in the recess or pocket 15 20 with one end extended out through one or the other holes 29 or 30, the wedge-block is introduced into the pocket through the entrance or mouth 21, the bolt being so held in place that as the wedge-block drops into the 20 pocket the bolt-head 27 will be received in the undercut portion of the recess 26. The wedge and block are then pushed to one side, as is indicated in Fig. 4, and the lock-block 22 introduced into the pocket through the 25 mouth 21, the position of the wedge being such as to allow the lock-block to drop into the pocket sufficiently to permit the brake-head hub to be slid lengthwise on to the sleeve 12. When being placed on this sleeve the brake-head 30 is turned around so as to permit the inwardly extended finger or projection 35 to enter the slot 14 through one of the mouths or entrances 15 or 16, and after this projection 35 has entered the slot 14 the brake-head 35 may be turned angularly on the sleeve and brake-beam to proper position, after which the nut 31 is screwed on the threaded portion of the bolt 28 so as to draw up the wedge 25, the latter by co-operation with the lock-block 22 projecting the latter into the groove 14 until the roughened surfaces at the bottom of the groove and on the concave face of the lock-block come into firm engagement and act to hold the brake-head in adjusted 40 45 angular position. When this position of the parts has been secured, the nut lock 32 is bent up so as to prevent unturning or loosening of the nut.

If desired, the lock-block 22 may fit somewhat loosely in the pocket, so that if the corrugations or serrations of the co-operating roughened surfaces do not exactly match in the adjusted position of the brake-head, plenty of room will be provided for the 50 55 proper intermeshing of the small teeth, it being understood that the device is capable of holding the brake-head in position merely by the friction exerted between the sleeve and brake-head through the lock-block and sliding wedge.

The kind of sleeve illustrated on the drawings is adapted for use at either end of the brake-beam, and for that reason the slot 14 is preferably provided with two entrances

or mouths 15 and 16, either of which may be 65 employed for admitting the projection 35 into the groove. Whereas but one roughened surface is indicated as being in use in Fig. 1; the upper or inoperative serrated surface would be employed for retaining the head 70 in place if the sleeve were used at the opposite end of the brake-beam.

It is to be understood that this invention is not limited and restricted to the precise construction shown and described, because the minor mechanical features thereof may be modified within wide limits without departure from the scope and essence of this invention.

I claim:

1. In a device of the character described, the combination of a brake-beam, a brake-head adapted to fit on the end of said brake-beam, a lock-block, and unyielding means carried by the brake-head and adapted to 85 actuate said block to maintain said brake-head in adjusted angular position on said brake-beam, substantially as described.

2. In a device of the character described, the combination of a brake-beam, a brake-head adapted to fit on the end of said brake-beam, a lock-block, and unyielding means carried by the brake-head and adapted to force said block against the brake-beam to prevent turning of the head thereon, substantially as described.

3. In a device of the character described, the combination of a brake-beam, a brake-head adapted to fit on the end of said brake-beam, a lock-block housed in said brake-head, and unyielding means in said brake-head and adapted to force said block against the brake-beam to prevent turning of the head thereon, substantially as described.

4. In a device of the character described, the combination of a brake-beam having a roughened surface, a brake-head adapted to fit on the end of said brake-beam, a lock-block with a roughened surface in said brake-head, and unyielding means to force the roughened surface of said block against the corresponding surface of said brake-beam to prevent turning of the head thereon, substantially as described.

5. In a device of the character described, the combination of a brake-beam, a brake-head adapted to fit on the end of said brake-beam, a lock-block, and wedge means to force said block against the brake-beam to prevent turning of the head thereon, substantially as described.

6. In a device of the character described, the combination of a brake-beam having a transverse groove, a brake-head adapted to fit on the end of said brake-beam, a lock-block in said brake-head adapted to extend into said groove, and wedge means to force said block against the bottom of said groove

to prevent turning of the head on the brake-beam, substantially as described.

7. In a device of the character described, the combination of a brake-beam having a 5 roughened surface, a brake-head adapted to fit on the end of said brake-beam, a lock-block with a roughened surface in said brake-head, and wedge means to force the roughened surface of said block against the roughened surface of said brake-beam to prevent 10 turning of the head thereon, substantially as described.

8. In a device of the character described, the combination of a brake-beam, a brake-head adapted to fit on the end of said brake-beam, a lock-block, a wedge to force said lock-block against the brake-beam to prevent 15 turning of the head thereon, a bolt in operative engagement with said wedge, and 20 a nut for said bolt, substantially as described.

9. In a device of the character described, the combination of a brake-beam, a brake-head adapted to fit on the end of said brake-beam and having a bayonet-joint connection 25 therewith, a lock-block in said brake-head adapted to bear against the bottom of the groove of said bayonet joint, a wedge to force said block against the bottom of said groove to lock the brake-head from turning on the 30 brake-beam, and means to actuate said wedge, substantially as described.

10. In a device of the character described, the combination of a brake-beam, a sleeve on the end of said brake-beam, a brake-head 35 adapted to fit over said sleeve, a lock-block in said brake-head, and wedge means to force said block against said sleeve to prevent turning of the head thereon, substantially as described.

40 11. In a device of the character described, the combination of a brake-beam, a grooved sleeve on the end of said beam, a brake-head adapted to fit on said sleeve, a lock-block in said brake-head adapted to project into said 45 groove, and wedge means to force said block against the bottom of said groove to prevent

turning of the head on said sleeve, substantially as described.

12. In a device of the character described, the combination of a brake-beam, a sleeve on 50 the end of said beam having a roughened exterior surface, a brake-head adapted to fit on said sleeve, a lock-block in said brake-head having a roughened surface adapted to co-act with the corresponding surface of said sleeve, 55 and wedge means to force said block against said sleeve to prevent turning of the head thereon, substantially as described.

13. In a device of the character described, the combination of a brake-beam, a sleeve 60 fitted on the end of said beam having a transverse groove with a roughened bottom surface, a brake-head adapted to fit on said sleeve, a lock-block in said brake-head having a roughened surface and adapted to be projected into said groove, a wedge to force the roughened surface of said block against the corresponding surface of said groove to prevent 65 turning of the brake-head on the sleeve, and means to actuate said wedge, substantially as described.

14. In a device of the character described, the combination of a brake-beam, a brake-head adapted to fit on the end of said brake-beam and having a bayonet-joint connection 75 therewith, consisting of a projection on said brake-head and a groove on said brake-beam, the bottom surface of said groove being roughened, a lock-block with a roughened surface in said brake-head, a wedge to force 80 the roughened surface of said block against the corresponding surface of said groove to prevent turning of the head on the brake-beam, a bolt operatively connected with said wedge, and a nut for said bolt, said nut and 85 bolt acting to actuate said wedge to operate said lock-block and force it against the brake-beam.
